US00D620674S

(12) **United States Design Patent**
Biegel

(10) **Patent No.:** **US D620,674 S**
(45) **Date of Patent:** **** Jul. 27, 2010**

(54) **CREMATORY URN**

(76) Inventor: **Achim Biegel**, Humweilerstrasse 73 b,
Oberthal (DE) 66649

(**) Term: **14 Years**

(21) Appl. No.: **29/340,897**

(22) Filed: **Jul. 28, 2009**

(30) **Foreign Application Priority Data**

Apr. 29, 2009 (EM) 001130793-0003

(51) **LOC (9) Cl.** **99-01**

(52) **U.S. Cl.** **D99/5**
